UNITED STATES PATENT OFFICE.

JAMES SPEAR, OF PHILADELPHIA, PENNSYLVANIA.

STOVE OR RANGE.

SPECIFICATION forming part of Letters Patent No. 521,827, dated June 26, 1894.

Application filed October 27, 1893. Serial No. 489,274. (No model.)

To all whom it may concern:

Be it known that I, JAMES SPEAR, a citizen of the United States, and a resident of the city and county of Philadelphia and State of Pennsylvania, have invented certain new and useful Improvements in Stoves or Ranges, of which the following is a specification.

My invention relates to improvements in cook stoves or ranges, and the object of my invention is to furnish a cook stove or range with a novel arrangement of fire pot, dust flue and grate, so combined as to increase the efficiency and convenience of the stove.

In the accompanying drawings in which similar letters of reference indicate similar parts throughout the several views, Figure 1, is a plan of a cooking stove or range furnished with my improvements; Fig. 2, a front elevation of the same; Fig. 3, a section of Fig. 2 on line 1—2; Fig. 4, a front elevation of part of the stove, the front wall being partly broken away to show the dust flue and damper; Fig. 5, a plan of the damper, and Fig. 6, a perspective view of the plate *b* and its connected parts.

A is a range or stove. *B* the fire pot. *C* the front wall of the stove. *D* the top. *E* a dust flue between the front wall of the stove and the fire pot. *F* a damper adapted to close the flue *E*. *G* an operating handle attached to damper *F* and which passes through front wall *C* and by means of which the damper may be operated. *H* a door in the front wall of the stove which is opened when it is necessary to rake the stove with a poker. The normal position of the damper is that shown by the full lines in the drawings, that is, extending from side to side of and closing the flue *E* so as to prevent the draft from passing through this flue.

When it is necessary to rake the stove with a poker the door *H* is opened and all the other doors and openings in the stove are closed, the damper *F* is moved so as to stand vertically, as shown by dotted lines in Figs. 2 and 4, thus opening flue *E*. A strong draft passes from outside the stove through door *H*, up through flue *E* and across the fire chamber and to the chimney, carrying with it all the

dust that may have been made by raking the fire, and effectually preventing the escape of any of this dust through door *H* to the room in which the stove is placed. The sides of the flue *E* are formed by projections *a*, *a*, Fig. 4, cast upon the plate *b*, against which the fire brick in the front of the fire pot rests, these projections touch the front casting of the stove proper and their lower parts are inclined from each other, as shown in Fig. 4, so that the flue is wider at its bottom than at its top in order to produce a better draft.

I is a grating that covers the top of flue *E* and prevents coal, &c., from falling into this flue, this grating forms part of the casting of plate *b*.

K is a cover or door which closes part of the front of the flue *E*. This cover or door may be removed or opened to adjust or replace the damper *F* should any accident happen to it.

In the drawings I have shown the range furnished with an oval fire chamber *B* the major axis of which is parallel to that side of the range upon which is the oven door, instead of at right angles as is the usual construction. A fire chamber arranged in this manner gives the attendant better access to the fire and to the oven than one arranged in the usual manner in broiling large articles, a large fish for example, it allows the handle 75 of the gridiron to project out at right angles to the front of the range where it can be much more readily handled than if it projected out from the side of the range, and this is particularly true when the rear part of the range 80 projects into a recess or is bricked into a wall, in which case the operator cannot stand at the side of the range but must stand at its front and reach forward to grasp the handles of the gridiron and turn it by a wrist motion 85 only, a difficult matter when the article being broiled is large and heavy.

Having thus described my invention, I claim—

The combination in a cooking stove or range of an oval fire pot the major axis of which runs lengthwise with the front of the stove, a plate *b* upon the front of the fire pot,

a grated lip extending from said plate *b* to | wall through which access may be had to said
said front wall, projections *a*, *a*, extending | flue and damper.
from said plate *b* to said front wall, said pro- |
jections being farther apart at their bottoms |
5 than at their tops and forming with the plate |
b and the front wall a flue *E*, a damper *F* |
within said flue *E*, and a door *K* in the front |

JAMES SPEAR.
